JOHN FEHL AND ALVA BELCHER, OF JERSEY CITY, NEW JERSEY

HOSPITAL BEDSIDE UNIT

Application filed April 10, 1931. Serial No. 529,024.

This invention relates to an improved hospital bedside unit.

In hospitals it is desirable to provide certain essentials for the care and comfort of a patient as well as for the use of the doctors and nurses, for instance: A dressing table for the convenience of the doctor and to support water pitcher, glasses, sputum cup and medicine for the patient, feeding trays or tables, costumers or rods clamped to the bed for the purpose of supporting a clysis bottle, a Murphy-drip container, an enema case, douche bag, or other irrigation device, also provision must be made for the care of the patient's clothing and toilet necessities. All these separate articles tend to clutter up the wards, the table often must be cleared for the doctor, feeding trays are frequently difficult for the patient to eat from due to his or her condition, and the use of a costumer or clothes tree is highly unsatisfactory, while the lack of provision for the personal belongings of the patient near him is undesirable. Where the present clothes tree is used for irrigation purposes the tree is usually placed at the foot of the bed in a direct line with the patient's vision, thereby causing him nervousness and annoyance. The container cannot be raised or lowered to another hook without removing from the hook which it is on causing the clysis needles or enema tubes to slip from their positions causing pain and discomfort to the patient. Only a few trees are kept in a ward as they are unsightly in appearance, collect dust and dirt, take up much needed space. Sometimes in case of emergency a tree is not available and some make shift is used such as fastening to the framework of a bedside screen. The rods that are clamped to the beds are also unsatisfactory as these are also in the line of the patient's vision, mar the paint, are a nuisance to set up and as the clamps and bolts are small they frequently become misplaced. If not securely fastened they are liable to slip causing serious conditions.

The present custom of keeping sputum cups on top of the bedside table is unsanitary and a source of annoyance for they are easily upset, and a jar of the table often slides

the cup beyond the patient's reach. As the sputum is sometimes desired for microscopic examination it is also essential that in such cases it be preserved.

It is desirable to keep the personal belongings of the patient near him for his greater peace of mind and comfort and this is impossible in most wards unless cabinets of some kind are provided.

The customary feeding trays are not satisfactory nor are the travelling tables on wheels as the patient has difficulty in comfortably using either of them.

One of the objects of this invention is to provide a bedside unit which provides a table, a surgical dressing table and convalescent feeding tray, bedside table and reading rack, clysis rod, sputum cup and holder, compartments for personal belongings, drawer and rack for papers and magazines combined in a single bedside unit which is compact and neat in appearance. A further object of the invention is to provide a bedside unit carrying a bedside table which is collapsible when not in use and adjustable for use to fit the requirements and comfort of the patient and which can be used as a reading rack, feeding table, etc. Still another object of the invention is the provision of a sanitary container for the personal effects of the patient. Other objects are an improved clysis rod in conjunction with a bedside unit, provision for a sputum cup container available to the patient but removed from the table. Other objects will appear more fully hereinafter.

Referring to the drawings:

Figure 1 is a view in front elevation of a bedside unit embodying the principles of our invention.

Figure 2 is a view in side elevation of the right side of Figure 1.

Figure 3 is a view in rear elevation.

Figure 4 is a partial plan view showing the bedside table extended for use.

Figure 5 is a partial view in side elevation showing the bedside table extended for use and its adjustability for different heights.

Figure 6 is a partial view in side elevation showing the bedside table top extended and elevated for use as a reading rack.

Figure 7 is a sectional view of Figure 6 along the line 7, 7, looking in the direction of the arrows.

In carrying out our invention we provide a bedside unit 1 having a flat top preferably of rubber 2, supported by container 3 preferably made of metal, below top 2, within container 3, we provide a drawer 4 and thereunder a slide 5. A compartment 6 is below slide 5 and is closed by door 7, having latch 8, an open end compartment 9 is below container 3 and is secured thereto. Legs 10 support container 3 and are provided with casters 11, which are connected to legs 10 by 10 toggle brakes 12 which can be engaged and disengaged with the foot. On one side we provide brackets 13, 14, 15, 16, having circular holes therethrough for rods 17, 18. A manually operated set screw 13' is carried by 15 bracket 13 to bear against rod 17 to secure it in any desired position as to height with respect to the bracket 13. Rod 17 is a part of an M frame 19 composed of rods 17, 21, 23, joined at top and bottom as shown while rod 20 18 is a part of a corresponding M frame 20 composed of rods 18, 22, 24. Bedside feeding table 25 is carried by frame 26 which latter has lugs 27, 28, sliding between rods 22, 24 and 21, 23. Rod 47 joining rods 23, 24, retains frame 26 upright when table is not in use and forming a support when the table is raised and swung through an angle of 90° to the horizontal, lugs 27, 28, bearing against the top junctions of rods 21, 23 and 22, 24. A 25 latch 29 holds top 25 to frame 26 on one side, top 25 being pivotally connected at 31 to frame 26 on the other side. Top 25 has an upturned side 30. When it is desired to use the feeding table as a reading rack, latch 29 is unfastened and table top 25 is raised as 30 shown in Figures 6 and 7. A pivoted U support 32 dropping into the desired notches 33 of cross frame supports 34, 35. Table 25 is again made available for use as a table by 35 raising it slightly and pushing U support 32 out of notches 33 and allowing top 25 to drop into the horizontal when latch 29 again snaps top 25 to frame 26. The height of table 25 can be adjusted by raising the rods 17, 18, in 40 their brackets to the desired height manually tightening set screw 13'. Top 25 when no longer desired for use is lifted by handle 36 secured to frame 26 to the vertical and allowed to slide down between rods 47, 47', until lugs 27, 28, rest at the bottom junctions of rods 21, 23, 22, 24. A rack 37 is secured to rods 21, 23, 22, 24.

The rear of the unit has bracket 38 for sputum cup container 39, hook 40 for the wash basin, towel rod 41, wash cloth rod 42, soap and toilet articles compartment 43.

We preferably construct the unit 1 of metal and the supporting legs 10 are hollow, such construction enables us to utilize one of the legs as a sheath for the extensible clysis rod

44, which consists of two or more sections 44', 44''. Section 44' is a hollow cylinder having a collar 45 and set screw 46 and section 44'' is a solid rod terminating in a hinged end portion 49 adapted to be swung to the horizontal to support an enema douche bag or other irrigation container. A set screw 48 is adapted to secure sections 44' at any height with respect to leg 10. The set screw arrangement also permits of rotation of rod 44'' by loosening set screw 46 and then tightening.

Slide 5 can be used as a convalescent table or for the convenience of the physician or nurse in making dressings.

Compartment 6 is available for the patient's clothing while compartment 9 is adapted for use for the patient's slippers and shoes removing them from the floor.

The rubber top 2 is particularly desirable as it is sanitary, can be washed, disinfected, reduces noise in the ward, prevents breakage of glassware. The sputum cup is removed from the top and yet is readily available to the patient. The toilet requisites are all on the rear out of sight and yet readily available. The mounting of the unit on casters together with its lightness makes it easily moved about by handles 50 while its sturdy construction together with the toggle brakes permits of a patient resting his weight safely thereon.

It will thus be seen that we have provided a compact bedside hospital unit of neat appearance that is sanitary and supplied in a single unit a noiseless top table, a bedside feeding table and reading rack, a surgical dressing table, a clysis rod, clothing compartment, a drawer for a patient's personal belongings, a magazine and paper rack, a slipper compartment, a toilet articles compartment and other conveniences for the patient, doctor and nurse.

What we claim is:

1. A bedside unit, a bedside feeding table carried by said unit, said bedside feeding table comprising a flat top, a frame supporting said top, said frame carrying lugs, said lugs adapted to slide in slots of supporting rods, supporting rods mounted on said unit, cross bars connecting said supporting rods at the top to retain said top and frame vertical and cooperating with said lugs and supporting rods to maintain said top and frame in horizontal position when said top and frame are vertically raised to their limiting position and lowered to the horizontal.

2. A bedside unit, a bedside feeding table carried by said unit, said bedside feeding table comprising a flat top, a frame supporting said top, said frame carrying lugs, said lugs adapted to slide in slots of supporting rods, said supporting rods mounted on said unit, cross bars connecting said supporting frames at the top to retain said top and frame

vertical and cooperating with said lugs and supporting rods to maintain said top and frame in horizontal position when said top and frame are vertically raised to their limit-
5 ing position and lowered to the horizontal, said supporting rods adjustable as to height in said mountings and means for securing

said supporting rods at any desired elevation. Signed at Jersey City, in the county of Hudson and State of New Jersey this 1st day of April A. D. 1931.
